OVERLOAD APPARATUS

Carl A. Rietz and Alvero E. Smith,
San Francisco, Calif.

Application August 2, 1940, Serial No. 349,662

1 Claim. (Cl. 200—112)

This invention relates generally to devices for the protection of electric motors, particularly in order to safeguard against overloads.

In the installation of various electric motors, such as motors used in various processing plants, it is customary to employ a starter having some protection against heavy overloads. Such protection, however, is arranged with a time delay before release of the starter, and is not capable of accurate adjustment to suit varying conditions and requirements.

It is an object of the present invention to provide apparatus which will afford instantaneous overload cutout for electric motors, and which can also be readily adjusted so that the extent of overload before cutout can be adjusted to suit requirements.

A further object of the invention is to provide an overload relay having means for varying both the point of cutout and pickup with respect to the current flow to the motor and also means for adjusting or varying the margin between cutout and pickup.

Additional objects of the invention will appear from the following description in which the preferred embodiment is described in detail in conjunction with the accompanying drawing.

Referring to the drawing:

Figure 1 is a plan view of an overload relay incorporating the present invention, and also showing certain connections between the relay and an electric motor together with its starter;

Figure 2 is a cross sectional view taken along the line 2—2 of Figure 1; and

Figure 3 is a wiring diagram.

Referring first to Figure 1 of the drawing, the apparatus includes an electric motor 10 which in this instance is operated on three phase alternating current. The conductors T1, T2 and T3 connected to this motor extend from terminals of a starter box 11. Current supply lines L1, L2 and L3 also connect with the starter box. It is presumed that the starter in this instance is provided with a magnetic coil, which when energized or de-energized will result in instantaneous tripping of the starter to interrupt current supplied to the motor.

The overload relay 12 is used in conjunction with the above mentioned trip coil of the starter. This relay includes the electromagnet 13 which has a winding 14 and spaced magnetic pole pieces 15. The entire electromagnet together with other parts of the relay are secured to a suitable mounting plate or panel 16. In order to make possible a certain type of adjustment, the magnetic core for winding 14 includes one section 17, and another section 18 which is in the form of a threaded plug and which can be turned to advance or retract it with respect to the core section 17. By this arrangement the

air gap 19 between the sections 17 and 18 can be adjusted, to thereby adjust the strength of the magnetic field between the pole pieces 20.

Mounted between the pole pieces 20 there is a magnetic armature 21, which has a pivotal connection 22 to the fixed supporting plate 16. This armature may oscillate between two limiting positions, one of which is adjustable. One limiting position is established by the shoulder 10 24 on one of the pole pieces 20, and the other by the adjustable stop screw 26 which is carried by the bracket 27. Normally the armature is urged against the stop screw 26 by the spring 28. Tension upon this spring can be adjusted, 15 as by having the spring anchored to an upwardly bent arm 29, which is carried by a bracket 31. By turning arm 29, the angle of pull of the spring 28 with respect to the armature 21 can be adjusted, thus in effect varying the bias upon the armature.

20 The contacting means for the relay is a switch unit 32 of the Mercoid type, which is adapted to be tilted between off and on positions. The flexible leads 33 from unit 32 connect to the terminals 34 and 36. This unit or cartridge is 25 removably clipped within a mounting 37, which in turn has a pivotal connection 38 to the supporting plate 39. For reasons to be presently explained, plate 39 is secured to panel 16 in such a manner as to permit lateral adjustments, as for example by providing the slot 41 to accommodate the attachment screws 42.

In order to operably connect the mounting 37 to armature 21, the mounting is provided with an arm 43, the free end of which carries a pin 44. Pin 44 engages one side of an arm 45 extending at right angles to the armature 21. Mounting 37 is also biased in a counterclockwise direction as viewed in Figure 1, by means of the attaching 40 spring 46. Tension upon this spring can be adjusted by changing the setting of the anchoring screw 47. It will be evident that turning of armature 21 in a counterclockwise direction as viewed in Figure 1 causes switch unit 32 to 45 turn in a clockwise direction, and that as the armature turns toward its limiting position, the Mercoid switch unit will reach a position in which its inner contacts will be opened or closed, as the case may be. Preferably such operation 50 of the Mercoid switch unit takes place for movement of the armature from its limiting position shown in Figure 1, to another position short of engagement with the stop 24.

55 Connection of the relay described above with the motor 10 and the starter 11 is as follows: The terminals 49 of winding 14 are connected in series with one of the current supply conductors leading to the motor 10. In this connection it should be noted that the resistance or impedance of the winding 14 should be relatively

low so that normal operation of the motor is not impaired. Terminal 36 of the Mercoid switch unit is shown connected by conductor 51 to a terminal 52 on starter box 11. Another terminal 53 on the starter box connects through the manual switch 54, to the terminal 34, by way of conductor 55. Movable contacts 56 of manual switch 54, when open circuited, interrupt the connection between conductor 55 and terminal 53 of the starter box. Movable contacts 57 when closed serve to short out the Mercoid switch units. Assuming now that the relay is adjusted for cutout at 100% overload, the motor will function normally for all ordinary loads, and because of current flow through winding 16, magnetic flux will act upon armature 21 to hold this armature in an intermediate position away from the backstop screw 26. If a 100% overload occurs upon the motor 18 current flow to the motor is increased to a value sufficient to cause the armature 21 to turn to a position to operate the Mercoid switch unit 32. Thus the contacts of this switch unit are opened, and as a result the trip coil within the starter 11 is operated immediately to release the starter and thus interrupt supply of current to the motor. After the load upon the motor 18 has been removed, one may again start the motor by operating contacts 52 of the manual switch 54, together with manual operation of the starter 11, if the starter is of such a character that such manual operation is required.

The overload relay described above has certain desirable characteristics. By changing the setting of the core section 18, it is possible to adjust the percentage overload at which the relay will cut out and interrupt supply of current to the motor. Such adjustment will maintain the same general margin between cutout and pickup. In other words, if the relay is arranged to cut out at 100% overload, and to again close the Mercoid switch unit at 80% overload, the margin between 80 and 100% will be retained after adjustment of the core section 18, although after such adjustment the relay may cut out at say 150% overload, and pick up at say 130% overload. It is also possible to adjust the margin between cutout and pickup conditions. This is accomplished by adjusting the position of the mounting plate 39, for the Mercoid switch unit. A shifting of this plate from one position to another has the effect of changing the angle of switch unit 32 for a given position of the armature 21. Therefore, the relay can be made quite sensitive so that a relatively small amount of movement of the armature 21 away from the adjustable stop 26, will serve to shift the Mercoid switch unit between closed and opened positions. Additional adjustment can be made by changing the stop screw 26, and by changing the bias afforded by spring 28. A change in the bias of spring 28 makes possible relatively fine adjustment, thus making it possible to adapt the relay to particular requirements after a general setting has been made by turning the core section 18.

Figure 3 illustrates a system making use of two motors, where a condition of overload upon one motor acts through the overload relay for starting and stopping the second motor. Thus in this case one motor 61 operates a disintegrator 62, as for example a machine of the type disclosed in my Patent No. 2,153,590. Another motor 63 drives a feeder 64, as for example a feeder of the screw type, which supplies material to

the disintegrator 62. The starter 67 connects between the current supply line and the motors 61 and 63. The terminals 49 of winding 14 are connected in series with one conductor leading 5 to motor 61. One terminal 34 of the Mercoid switch unit 32 is connected by a conductor 68 to the terminal 69 of starter 67. The other terminal 36 of Mercoid switch unit 32 connects through the manual switches 71 and 72 to the terminals 52 and 53 of starter 66, as illustrated. Switch 72 is usually located at a remote point, closing of contact 74 being for starting of motor 61, and opening of contact 73 being for stopping. Closing of switch arm 76 of switch 71 places 10 motor 63 under the automatic control of the relay 12, while closing of arm 77 shuts out the Mercoid switch unit 32, and places motor 63 under the full manual control of the switch 72.

To explain operation of the system illustrated 20 in Figure 3, it will be presumed that the relay 12 is set to operate when a 100% overload is placed upon the motor 61. At the same time it will be presumed that feeder 64 normally supplies an amount of material to the disintegrator 25 62, such as will maintain a torque upon the motor 61 corresponding to the full rated capacity of the motor. A greater load upon the motor 61 will be because of a greater amount of material being fed to the disintegrator by the feeder 64. If the disintegrator is supplied with material such that a 20% overload is placed upon motor 61, relay 12 is set to trip Mercoid switch 30 32 to immediately cause interruption of current supply to the motor 63. When the disintegrator 35 clears itself and the load returns to normal, the current flow to the motor 61 is again reduced so that the relay 12 operates through starter 67 to re-establish current supply to motor 63. In this connection it will be noted that the conductor 68 connects to a coil associated with starter 67, so that when this coil is energized by current flow through switch 32, the main current flow to motor 63 is interrupted. When switch 32 is open circuited, starter 67 automatically re-establishes current supply to the motor.

For the automatic operation described above, arm 76 of switch 71 should be closed, and arm 77 opened. Where hand operation is desired from a position adjacent the relay, switch arm 77 is 50 closed to shut out the Mercoid switch unit 32. Manual switch 72 can be located at a remote point, and serves to effect manual control of motor 61, through starter 66.

We claim:

55. In an overload relay, an electromagnet having a winding and also having spaced magnetic pole pieces, the winding being adapted for connection in series with a current carrying circuit, a pivotally mounted armature associated with the 60 pole pieces, means for biasing the armature toward one of two limiting positions, a switch unit of the Mercoid type, a rocker mounting for the switch unit pivotally secured to a fixed support, whereby the switch unit is free to tilt between 65 on and off positions, means for urging the rocker mounting in one direction and a pair of engaged lever arms secured to the armature and to the rocker mounting respectively for causing rocking of the mounting when the armature is rotated, and means for shifting the pivotal axis of the rocker mounting relative to the pivotal axis of the armature.
